BUILT-UP CONTAINER

Irving Goldman, New York, N. Y.

Application February 19, 1949, Serial No. 77,349

3 Claims. (Cl. 206—7)

1

This invention relates to new and useful improvements in readily erectable collapsible containers made of a foldable material, such as corrugated board, and, more particularly, the aim is to provide a novel and valuable such container which may be inexpensively and otherwise entirely practicable embodied, among other ways, as either a one-piece container structure or as a plural-piece container structure.

According to one way of carrying out the invention, a suitcase-like hand-portable container is provided, of smaller cubic content than the larger container constituting the other of the two types of container pursuant to the invention and herein illustratively shown; said container of smaller cubic content preferably being the one which incorporates a one-piece container structure.

According to another way of carrying out the invention, a storage and shipping container is provided, this the said container of larger content above referred to, with the same constituting a container of such height that a plurality of garments, as women's dresses may be suspended therein in a manner to preserve the garments against crumpling, rumpling or other temporary or permanent damage or effect detrimental to their ready-for-sale or ready-for-use condition, during storage or shipping.

While in the use of the hand-portable container of the invention the garments, if of such length as men's trousers and women's dresses, are not freely suspendable, they nevertheless are confined and held so that they may be loosely doubled on themselves and in a way also to preserve them against deterioration from unrumpled and clean condition.

Each of the two containers constituting the embodiments of the invention above alluded to may be provided with a swing door, as at the front thereof; and in the case of both these containers interlocking or interfitting parts are included by means of which, or by the aid of which, the container, when erected, packed and closed, may be dependably sealed closed.

Each of the containers has a movable top or roof section, and in this connection a cooperant feature is the provision of slideway affording means, as additions to the main container structures; said means incorporating rails along which, depthwisely of the container, a plurality of special garment hangers, the nature of these also constituting a feature of the invention, may be arranged, each such hanger for suspending one or more garments from a point on the latter, as a point thereon high up on the same.

2

A further feature of the invention is that said slideway means are merely hook-on elements, practicably fabricable as thin metal strip-like stampings and so at negligible cost, and so cross-sectionally shaped that they may be securely locked in place when said movable top or roof section of the container is applied or lowered to closed position.

Still another feature of the invention is the provision of a rack-bar-like element for cooperating with a plurality of the new hangers on the new trackway means, to space said hangers predeterminedly depthwisely of the container.

Still a further feature of the invention is the provision of a spring-arm element, of Z extension, for use in coaction with one or more hangers in the container, with these hangers so few in number as to be loose in the container, to prevent shifting and rattling of the hangers.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a now favored form of the aforesaid hand-portable container embodiment of the invention, showing the same closed, as when holding a plurality of garments therein pursuant to the invention.

Fig. 2 shows a single blank, of corrugated board or the like, for being folded on itself to constitute the entirety of the main body of the container shown in Fig. 1.

Fig. 3 is a horizontal section, taken substantially on the line 3—3 of Fig. 1.

Fig. 4 elevationally shows one of the above mentioned hangers; the same being formed of unitary planar fairly rigid yet fairly thin sheet material, as, for example, so-called fibre or fibre-board.

Fig. 4A is a fragmentary perspective view of one of two like members to constitute the above mentioned slideway means.

Fig. 5 is also a fragmentary perspective view, but this showing an upper end portion of the container of Fig. 1, with now added thereto a pair of said members in the manner shown in the case of the one thereof seen in this view.

Fig. 6 is a horizontal section, taken on the line 6—6 of Fig. 5.

Fig. 7 is a perspective view showing plurally fragmentarily the already mentioned spring arm 55 of Z extension.

Fig. 8 elevationally shows the already mentioned rack-bar-like element, as adapted for use with the container of Fig. 1 when such container is equipped as explained above in connection with Fig. 5.

Fig. 9 is a perspective view of a full-length storage and/or shipment container pursuant to the invention; said container, shown in this view as broken away intermediate its upper and lower ends over a major part of the height thereof, being illustrated in closed condition, with adhesive strips applied at the joints thereof.

Fig. 10 is also a perspective view, showing the full height of the container, but with the separate top and bottom end sections, to be telescopically applied to the main body of the container, not yet thus applied.

Fig. 11 is a horizontal section, taken on the line 11—11 of Fig. 12.

Fig. 12 is a vertical section, taken on the line 12—12 of Fig. 9.

Fig. 13 is a vertical section, taken on the line 13—13 of Fig. 9.

Fig. 14 is a plan view, looking down on the top of the main body of the container, and with a plurality of the hangers on the slideway means and with a Z-extension element pursuant to the invention applied to hold all the hangers relatively close to a selected vertical wall of the container.

Fig. 15 shows the blank of corrugated board or the like which is folded up to provide the main body of the container.

Fig. 16 (this view substantially the same as Fig. 4A) is a fragmentary perspective showing of one of the two like members to constitute the slideway means for the contained hangers.

Fig. 17 (this view corresponding, as to general subject matter, to Fig. 8) side elevationally shows the rack-bar-like element as adapted for use with the container of Fig. 9.

Fig. 18 is a plan view of such an end section as is seen near the bottom of Fig. 10; said section shown in collapsed condition.

Fig. 19 shows the blank from which such an end section is formed.

Fig. 20 (this view substantially the same as Fig. 7) is a perspective view showing plurally fragmentarily the Z-extension spring arm element.

Referring now to the drawings more in detail, and first to Figs. 1-8, the container here illustrated is as a whole designated 25. The same is made by folding up on itself, along the broken lines indicated in Fig. 2, the blank 25^a there shown.

Said blank has a back wall section 26, a front wall section 27, two like side-wall-panel flaps 28, two like complementary side-wall-panel flaps 29, a bottom wall section 30, two like bottom-cupping tabs 31, and a top wall section 32.

When the blank 25^a is folded up on itself in a manner obvious from what has just been said, the vertically extended (in Fig. 1) rear marginal edges of the flaps 29 may be arranged slightly to overlap the forward marginal edges of the flaps 28; with then all the members 26, 27, 28 and 29 perpendicularly offset from the floor section 30, so that when the top or cover section 32 is swung down as in Fig. 1 the entire upper end of the container is roofed over in a satisfactorily tight manner. As shown in Fig. 3, the bottom-cupping tabs 31 at this time are upstanding and caught behind the panels 28 and 29.

For interlocking each panel 29 to the adjacent panel 28, each of said panels 28 has a slot 33 therethrough, this for coaction with a tab offset 34 appropriately from a panel 29; these tabs 34 being alike, and both being of truncated triangular outline and inwardly tapering toward their root portions.

For interlocking the lowered top or cover section 32 with the front wall section 27, the latter has a slot 35 therethrough, this for coaction with the bill end of a hook-shaped projection 36 offset from the swinging edge of said top section 32.

Said top section 32 is shown as carrying, upwardly extending from its upper surface when lowered, a handle 37, which may be and preferably is a strip of textile or other strong sheet material glued or otherwise suitably attached at its terminal portions to the section 32 between an upwardly bowed intermediate portion of said strip.

One of the plurality of like hangers provided is shown at 38 in Fig. 4, and several thereof are seen in top plan in Fig. 6. Each such hanger has a main bar-like top length, near opposite ends of which at the bottom thereof are upwardly extending notches 38^a, 38^b. Between said notches the hanger incorporates a central reduced neck portion 38^b integrally suspending a hanger-proprietor portion 38^c.

At 39 are shown the strip-like members to be used as a pair thereof to provide the slideway means of the invention. Each such fitment 39 includes, extending longitudinally thereof, an intermediate vertical flange 39^a, a hook-over terminal preferably narrower flange 39^b, an outer horizontal flange 39^c, a rail 39^d, and an inner horizontal flange 39^e. These parts are so arranged that with said pair of fitments attached to the upper ends of the side walls 28—29 of the container as erected in Fig. 1 (of course before lowering the top section 32), a number of the hangers 38, to any total appropriate to the dimension of the container in a direction parallel with said side walls, may be suspended from the rails 39^d and slidably therealong; with said rails in the notches 38^a.

The just-mentioned attachment of the two fitments 39 to the side walls of the container is at the downwardly facing grooves of said fitments 50 afforded between the flanges 39^a and 39^b thereof. Squeezing of the overlapped portions of the panels 28 and 29 into these grooves assists in maintaining the container in erected condition. The locations of the fitments 39 relative to the side 55 wall panels 28 is indicated in dot and dash lines at 39' in Fig. 2.

The rack-bar-like device already referred to is shown at 40 in Fig. 8. The inter-teeth spaces thereof are of a width conforming to the thickness of the sheet material of which the hangers 60 38 are made, as by stamping out the same.

The spring-arm device of Z-extension already referred to is shown, detached, in Fig. 7 at 41; and the mode of utilization thereof is clearly 65 shown in Fig. 6.

At 42, 42 in Fig. 1 is illustrated the use of a suitable plurality of suitably placed adhesive strips; which desirably are of the pressure-adhesive type, as is characteristic of so-called 70 draftsman's Scotch tape.

Referring now to the form of the invention illustrated in Figs. 9-20, this includes a collapsible box member 10 having side walls 10L and 10R, a back wall 10B, and a front portion 10F comprising a door having end flap 10F2. Extension flaps 75

10L1, 10B1, 10R1, and 10F1 are preferably attached to the bottom end portion of the side, back and front walls and folded on lines 11 to form a two-layer integral bottom for the built-up container (see Fig. 10). The side walls fold on lines 12, for collapse of the container into a flat package.

The built-up top section 13 and the similar bottom section 14 are telescoped over the end portions of the built-up four walls, to enclose a compartment therewithin.

Fig. 16 shows a rail 15 preferably formed from a flat strip to include a vertical flange-hook 151 to provide a hanger portion for removably fitting over the upper side wall edges 10LE and 10RE. The said rail provides a track 153 having at one side a groove 152 and a horizontal ledge 155 at its other side. The length of said rail is such as to endwisely abut the front 10F and back 10B, to prevent longitudinal movement of the two rails employed.

The garment hanger 16 (Figs. 10, 12, 13 and 14) is provided with notches 161 for slidably engaging the tracks 153 of the two rails 15. The hanger is shaped in the manner familiar in coat hangers, and a slot 166 may be provided to facilitate the hanging of trousers, etc. Depressable spacer fingers 167 may be provided in suitable size, number and place, and defined by suitable lines of weakness 168.

A suitably toothed spacer bar 17 (Fig. 17) is provided, this having its teeth 171 arranged to receive hangers 16 therebetween and to hold them in spaced relation. These teeth may be of uniform width to provide uniform spacing of the hangers; but bars may also be provided having teeth of different widths to vary the relative hanger spacing.

In Fig. 10 at 17^a is shown a spacer, special to each hanger and integral therewith; with one such spacer 17^a at each end of a hanger.

At times a partly filled container (note Fig. 14) must necessarily be shipped. To hold said few hangers in locked position, a spring lock bar such as 18 (Fig. 20) is removably inserted as shown (Fig. 14), with one end 181 abutting the outer hanger 16 and its other end 182 abutting the closed front door 10F.

In assembling the container, preparatory to packing the same, I prefer to stand the integral wall members on their bottom portions, and then to fold inwardly the end flaps 10L1, 10B1, 10R1 and 10F1, thereby to cause the members 10L1 and 10R1 to be parallel with members 10B1 and 10F1 but overlying them. The door 10F of course is left open to provide passageway for the merchandise to be packed. The hangers with the garments thereon are then slid along the slideways provided by the rails 15, and when the compartment is suitably filled, the door is closed, and flap 10F2 is sealed in place, preferably with gummed paper tape as indicated at 20.

After this, the top section 13 is telescoped over the upper end of the main body of the container.

The bottom section 14 is then telescoped over the lower end portion of the main body of the container, and suitably attached, as for example, by gum paper tape 20^b.

The bottom section 14, however, may be placed in position prior to packing, but in such case the flap 14F will not as yet be secured to tabs 14T. After the door 10F is closed, the said flap 14F may be secured in a suitable manner, as with staples. In this latter method, then, the top section 13 is the last end section applied. Also, a door flap

such as 10F3 may be biased to easy folding, to permit the door to close when the bottom is already in place.

To form the top and bottom sections, their flaps are folded up at right angles to portion 14B, and the tabs 14T are then folded about fold line 14L to lie against the outer side surface of flaps 14F to form a rectangular coverless box having sides that may hingedly collapse to form a flat object for more economical storage and shipping. The box unit formed by the joined side is collapsible on fold lines 14C and 14M to assume the condition shown in Fig. 18.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A housing container for a plurality of garments to be confined therein while suspended from a plurality of slidably mounted hangers therein, comprising a collapsible container unit formed by folding a blank on itself to provide a main structure including a back wall, a pair of side wall components, and a front wall constituted as a swingably openable and closable door, the said container also including a bottom section and a top section, said bottom section for placement to close the bottom of the container and said top section being movable relative to said side wall components for placement to roof over the top of the container and for other placement to open up said top, and a trackway means extending, in terms of the container when erected and upright, substantially horizontally and in a direction perpendicular to said back wall, said trackway means comprising two like fitments each longitudinally thereof having a hook-over formation for frictionally embracing the opposite sides of the top of a different one of said side wall components and each longitudinally thereof and inwardly of said formation formed to incorporate a rail substantially of inverted-U cross-section, whereby when said top section is secured in its first-named placement both said fitments are locked against disengagement from said side wall components, there also being provided a plurality of hangers having undercut notches shaped cross-sectionally in correspondence with the cross-sectional shape of said notches, said container being folded up from a single blank having integral subdivisions respectively providing said back wall, said top and bottom sections, said side wall components and said door, said subdivisions including four subdivisions for establishing both said side wall components, there being two such subdivisions for each side wall component with one thereof in the form of an elongate flap and the other thereof also in the form of an elongate flap.

2. A housing container for a plurality of garments to be confined therein while suspended from a plurality of slidably mounted hangers therein, comprising a collapsible container unit formed by folding a blank on itself to provide a main structure including a back wall, a pair of side wall components, and a front wall constituted as a swingably openable and closable door, the said container also including a bottom section and a top section, said bottom section for

placement to close the bottom of the container and said top section being movable relative to said side wall components for placement to roof over the top of the container and for other placement to open up said top, and a trackway means extending, in terms of the container when erected and upright, substantially horizontally and in a direction perpendicular to said back wall, said trackway means comprising two like fitments each longitudinally thereof having a hook-over formation for frictionally embracing the opposite sides of the top of a different one of said side wall components and each longitudinally thereof and inwardly of said formation formed to incorporate a rail substantially of inverted-U cross-section, whereby when said top section is secured in its first-named placement both said fitments are locked against disengagement from said side wall components, there also being provided a plurality of hangers having undercut notches shaped cross-sectionally in correspondence with the cross-sectional shape of said notches, said container being folded up from a single blank having integral subdivisions respectively providing said back wall, said top and bottom sections, said side wall components and said door, said subdivisions including four subdivisions for establishing both said side wall components, there being two such subdivisions for each side wall component with one thereof in the form of an elongate flap and the other thereof also in the form of an elongate flap, the sum of the widths of the two flaps of each of the last-named subdivisions being greater than the width of said bottom section.

3. A housing container for a plurality of garments to be confined therein while suspended from a plurality of slidably mounted hangers therein, comprising a collapsible container unit formed by folding a blank on itself to provide a main structure including a back wall, a pair of side wall components, and a front wall constituted as a swingably openable and closable door, the said container also including a bottom section and a top section, said bottom section for placement to close the bottom of the container and said top section being movable relative to said side wall components for placement to roof

over the top of the container and for other placement to open up said top, and a trackway means extending, in terms of the container when erected and upright, substantially horizontally and in a direction perpendicular to said back wall, said trackway means comprising two like fitments each longitudinally thereof having a hook-over formation for frictionally embracing the opposite sides of the top of a different one of said side wall components and each longitudinally thereof and inwardly of said formation formed to incorporate a rail substantially of inverted-U cross-section, whereby when said top section is secured in its first-named placement both said fitments are locked against disengagement from said side wall components, there also being provided a plurality of hangers having undercut notches shaped cross-sectionally in correspondence with the cross-sectional shape of said notches, said container being folded up from a single blank having integral subdivisions respectively providing said back wall, said top and bottom sections, said side wall components and said door, said subdivisions including four subdivisions for establishing both said side wall components, there being two such subdivisions for each side wall component with one thereof in the form of an elongate flap and the other thereof also in the form of an elongate flap, the sum of the widths of the two flaps of each of the last-named subdivisions being greater than the width of said bottom section, said container having slot and tab interlock means integrally carried by said blank.

IRVING GOLDMAN.
